FURNACE FOR PRODUCING PURIFIED METALS

Maurice L. Wood, Waterbury, Conn., assignor to
The Chase Companies, Incorporated, Water-
bury, Conn., a corporation

Application August 28, 1933, Serial No. 687,923

2 Claims. (CL 13—29)

This invention relates to improvements in producing purified metals, and more particularly, metals such as copper, copper alloys and the like.

Heretofore in the production of copper and copper alloys, the finished product frequently contained considerable amounts of non-metallic inclusions, oxides, etc. In particular, alloys containing appreciable amounts of aluminum or silicon or nickel are prone to give rise to these impurities. Needless to say, these inclusions are very detrimental to the casting and to products fabricated therefrom.

It has been common in the art to cover the surface of the molten metal with a layer of charcoal. While this layer of charcoal prevents excessive oxidation, it is not particularly effective in cleansing the metal of oxide particles already present. Furthermore, when such molten metals covered with charcoal are poured in the ordinary manner from the top, even with the greatest care to hold back the surface dross, since the metal is poured from the top, these inclusions become mechanically tangled in the resulting casting. Moreover, the layer of charcoal gives rise to gaseous impurities in the metal, namely, carbon monoxide and carbon dioxide, which are formed from the burning of the charcoal. These gases tend to produce holes and pockets in the cast metal.

One object of this invention, therefore, is to provide an improved process for producing purified metals, whereby these non-metallic inclusions, oxides, etc., are substantially eliminated from the metals.

Another object of the invention is to provide an improved process for producing purified metals, whereby gases such as carbon monoxide and carbon dioxide are substantially eliminated therefrom.

Another object of this invention is to provide an improved apparatus whereby the foregoing improved process can be readily and efficiently carried out.

With the above and other objects in view, this invention includes all improvements over the prior art which are disclosed in this application.

In the accompanying drawings, in which one way of carrying out the invention is shown for illustrative purposes:

Fig. 1 is a front elevation of an induction furnace made in accordance with this invention;

Fig. 2 is an elevation, mostly in section, on line 2—2 of Fig. 1; and

Fig. 3 is an elevation, mostly in section, on line 3—3 of Fig. 2.

The induction furnace 10 has an outer metal casing 11 provided with a lining 12 of electrical insulation. Within said insulation lining 12 is refractory material 13. The main chamber 14 of the furnace is provided to hold the main body of molten metal 15. The pouring-spout 16 extends from outside the furnace inwardly and downwardly to communicate with the main chamber 14 at the location 17 adjacent the bottom of the main chamber. The opposite leg-portions or leg-chambers 18 and 19 extend downwardly from the bottom of the main chamber 14 and are directed toward each other at their lower ends so as to be joined together at their lowest locations at 20 to form a complete loop 21. Thus, when the furnace is charged with metal, the molten metal not only occupies the main chamber 14, but extends downwardly to fill the loop 21 formed by the leg-portions 18 and 19.

Extending transversely through the loop portion 21 is an iron core 22 which will ordinarily be formed of laminations in the usual manner. The opposite ends of this core 22 are preferably magnetically connected with each other by similar iron laminations 23, 24, 25, etc. Surrounding the core 22 is a coil 26 having a plurality of helical turns of copper ribbon or wire 27, as is usual. The coil 26 ordinarily is supplied with an alternating current of suitable frequency in the well-known way. It will be evident that the loop 21 of molten metal forms a complete single turn of the secondary winding of a transformer of which the coil 26 forms the primary winding, all as is well understood by those familiar with the art of induction furnace construction.

The top of the surface of the metal 15 is covered with a layer of molten slag 28.

In operation, the alternations of the electric current induce a heavy current in the loop 21 of metal, causing considerable heating of the leg-portions 18, 19 thereof. Due partly to this heating action in the leg-portions of metal which extend downwardly, and partly due to the violent stirring action of the electric current, metal surges upwardly with considerable speed and force from the leg-portions 18 and 19 in the directions indicated by the upwardly-extending arrows (Fig. 3). Thus, molten metal is brought up from the depths of the bath of metal against the underside of the liquid slag layer 28, thereby permitting the slag to come in contact with the non-metallic inclusions and particles of oxide, resulting in these inclusions, oxides, etc., coalescing with or becoming entrapped in the slag layer, thereby resulting in the inclusions and oxides being eliminated from

the body of metal and retained by the covering of slag.

This violent stirring action that takes place is continued until the steady purifying action that 5 takes place by the oxides and other non-metallic inclusions contacting with and becoming entrapped in the liquid slag layer, results in the metal becoming substantially free from non-metallic inclusions, oxides, etc. At the same time 10 that this removal of non-metallic inclusions is taking place, the liquid slag layer acts as a perfect blanket to prevent the absorption of gases by the metal, and as the slag itself contains no gases, as 15 is true of charcoal, the metal is thus protected against absorption of gases.

After this purifying action has proceeded sufficiently to substantially remove the various objectionable inclusions, the metal is then poured from the furnace into suitable molds through the 20 pouring-spout 16. Inasmuch as this pouring-spout 16 connects with the main chamber 14 only at a location well below the liquid slag layer 28, there is no possibility of entraining or trapping 25 any portion of the slag layer with the metal during pouring, as would occur if pouring-spout 16 were so located as to permit the top surface of the metal and slag to be poured off the metal into the molds. Thus, the finished product has a maximum degree of purity, freedom from inclusions of 30 non-metallic particles, slag, gases, etc.

The invention may be carried out in other specific ways than that herein set forth without

departing from the spirit and essential characteristics of the invention, and the present embodiment is therefore to be considered in all respects as illustrative and not restrictive, and all changes coming within the meaning and equivalency range of the appended claims are intended to be embraced therein.

I claim:

1. A furnace for producing purified copper, copper alloys or the like comprising: a main 10 chamber for holding a quantity of molten metal; a leg chamber of relatively-small cross-sectional area communicating with the bottom of said main chamber and extending downwardly therefrom; means for heating metal in said leg chamber; and 15 a pouring spout communicating with said main chamber only adjacent the bottom thereof and well away to one side from the vertical planes enclosing said downwardly-extending leg-chamber.

2. A furnace for producing purified copper, copper alloys or the like comprising: a main chamber for holding a quantity of molten metal; a loop chamber communicating with the bottom of said main chamber and extending downwardly therefrom; 25 means for heating metal in said loop chamber; and a pouring spout communicating with said main chamber only adjacent the bottom thereof and well away to one side from the vertical planes enclosing said downwardly-extending 30 loop-chamber.

MAURICE L. WOOD.
